UNITED STATES PATENT OFFICE.

LARS L. SOLEM, OF MINNEAPOLIS, MINNESOTA.

BRUSH-HOLDER.

SPECIFICATION forming part of Letters Patent No. 592,838, dated November 2, 1897.

Application filed April 16, 1897. Serial No. 632,481. (No model.)

To all whom it may concern:

Be it known that I, LARS L. SOLEM, a citizen of the United States of America, residing at Minneapolis, in the county of Hennepin and State of Minnesota, have invented certain new and useful Improvements in Brush-Holders, of which the following is a specification, reference being had therein to the accompanying drawings.

10 This invention relates to brush-holders, and more particularly to that class in which the handle of the brush is clamped between two jaws and held securely therein.

The object of this invention is to provide a 15 brush-holder which can be secured to a handle of any length desired and one which can be adjusted to fit brush-handles of different sizes.

Another object of this invention is to provide 20 a brush-holder which holds the brush in such a position that when it is used from a scaffold or the ground the face of the brush is held flush against the object to be painted.

With these objects in view my invention 25 consists in the particular construction of the various parts and in the novel manner of combination or arrangement of said parts, all of which will be described hereinafter and pointed out in the claim.

30 In the drawings forming a part of this specification, Figure 1 is a view of my improved brush-holder as applied. Fig. 2 is a sectional view taken on the line $x-x$ of Fig. 1. Fig. 3 is a detail view showing the construction of 35 the brush-receptacle.

Referring to the drawings, A represents a 40 tubular casting of any suitable light and durable material, having its portion B provided with internal screw-threads a for the reception of a handle c . The portion D is cut away, as shown at b , and the sides of the said cut-away portion are forced out, forming a semicircular receptacle C, somewhat larger than one-half of the circumference of the portion B.

The aforesaid portion D is externally screw-threaded, as is shown at e . The relation of the notches d in the sides of the portion D are such with respect to each other that when a brush is placed therein it is held at an angle with the holder. Within the cut-away portion at the point f is hinged a clamping-jaw E, which is somewhat curved and adapted to fit in the semicircular receptacle C. It is also provided with notches which register with the notches d .

G is a thumb-nut operated by means of the thumb-pieces $h h$, by which it is made to traverse the screw e in operating the jaw E in clamping and unclamping the brush-handle.

It will thus be seen that by the peculiar 60 construction of this brush-holder any ordinary-size brush may be firmly held by the same. I also provide a light article which is simple in its construction, combining strength and durability, and one which will proficiently 65 perform all of its intended functions.

Having thus described my invention, what I claim as new, and desire to secure by Letters Patent, is—

In a brush-holder the combination of a 70 tubular casting, having its portion B provided with internal screw-threads for the reception of a handle, and its portion D cut away at b , the sides of the said cut-away bent out and notches in the said sides, the relation of these 75 notches being such to each other that when the brush is placed therein it is held at an angle with the holder, a clamping-jaw hinged in the said cut-away portion, and means for clamping the jaw and casting, substantially 80 as shown and described.

In testimony whereof I affix my signature in presence of two witnesses.

LARS L. SOLEM.

Witnesses:

HENRY J. GJERTSEN,
E. S. WETTSTEIN.
